ELI R. GREENE, OF DES MOINES, IOWA.

DRAFT-CONTROLLING MECHANISM FOR SMOKE-CONSUMING FURNACES.

1,157,097.

Specification of Letters Patent.

Patented Oct. 19, 1915.

Application filed January 25, 1915. Serial No. 4,389.

To all whom it may concern:

Be it that I, ELI R. GREENE, citizen of the United States of America, and resident of Des Moines, Polk county, Iowa, have invented a new and useful Draft-Controlling Mechanism for Smoke-Consuming Furnaces, of which the following is a specification.

The object of this invention is to provide means for mechanically controlling the draft devices in a forced-draft smoke-consuming furnace.

A further object of this invention is to provide an improved construction whereby a forced draft of air is admitted to a furnace immediately after coaling, to the end of consuming the smoke and gases incident to the young fire, and of mechanically and gradually opening the regular lower draft and then shutting off the forced draft for the normal control of the fire.

A further object of this invention is to provide means for controlling mechanically the forced and regular drafts of a furnace according to the condition of the fire.

My invention consists in the construction, arrangement and combination of elements hereinafter set forth, pointed out in my claims and illustrated by the accompanying drawing, in which—

Figure 1 is a front elevation of a portion of a furnace equipped with my improvements and showing the draft doors in closed position. Fig. 2 is a similar view illustrating the draft doors in open position. Fig. 3 is a plan, partly in section, illustrating the draft doors in open position. Fig. 4 is an elevation, partly in section and on an enlarged scale, of the driving mechanism employed. Fig. 5 is a sectional elevation at right angles to Fig. 4. Fig. 6 is a sectional elevation of the forced draft devices.

In the construction and application of the improvements as shown the numeral 10 designates generally a boiler furnace of any suitable construction, formed with fuel doors 11, 12 and draft doors 13, 14 therebeneath. An air pipe 15 is mounted transversely across the front of and within the furnace 10 and is formed with a plurality of branches or nipples 16 opening therefrom and directed rearwardly within the fire box of the furnace above the fuel doors 11, 12. The air pipe 15 is closed at its inner end and leads from some suitable point outside the

furnace such as a flue 17 from which said pipe receives a supply of atmospheric air. A pressure pipe 18 leads from a source of steam or compressed air supply and traverses the front of the furnace 10 parallel with and adjacent to the air pipe 15 and on the opposite side thereof from the nipples 16. The steam pipe 18 is formed with branches or jets 19 passing rearwardly through the air pipe 15 and projecting within the respective nipples 16. At times steam or compressed air is permitted to flow through the pressure pipe, by opening a valve 20 therein, and to pass out through the jets 19, thus creating a forced draft of air through the pipe 15 and nipples 16 to the end of furnishing an abnormal supply of oxygen to the fire on a plane immediately beneath the boiler of the furnace 10. This is especially desirable immediately after fuel has been added to the fire, to the end of consuming the gases released from such fresh fuel and creating a combustion of such gases high up in the fire box and immediately beneath the boiler, where it will be most effective. The extremities of the jets 19 and nipples 16 preferably are flattened or spread horizontally to distribute laterally of the furnace the streams of steam and air escaping therefrom.

It is desirable not to give the young fire much draft from below during the consumption of the gases as above described, as through the regular draft doors 13, 14, but to gradually open such doors and increase the draft from below as such consumption progresses, until said draft doors are fully opened and furnishing draft to the fire in the normal manner, whereupon it is desirable to stop the forced draft. For this purpose a motor or driving power is required, and I have shown a casing 21 mounted on one side of the furnace 10 adjacent the forward end thereof, in which casing is journaled a crank shaft 22, projecting at both ends from said casing. On the rear end portion of the crank shaft 22 is fixed and wound a leaf spring 23 having its opposite end secured by a bolt 24 to said casing. A cylinder 25 is mounted within the casing 21 and a piston 26 is adapted for rectilinear reciprocation therein and has its stem pivotally connected to the throw of the crank shaft 22. The casing 21 is adapted to contain a quantity of oil 27 or other suitable

fluid adapted to be drawn into the cylinder through a check valve 28 by upward movement of the piston 26 and to be discharged from said cylinder through a suitable valve 5 29 by downward movement of said piston, to the end of steadyng and governing the action of the shaft 22 and parts connected thereto. A pinion 30 is fixed to the forwardly projecting end portion of the crank 10 shaft 22 and is in mesh with and adapted to drive a pinion 31 fixed to a countershaft 31^a journaled for rotation in the casing 21. A crank handle or lever 32 is also fixed to the forwardly projecting end portion of the 15 crank shaft 22 and is adapted for manipulation to rotate the said shaft to set position and wind the spring 23 thereon. A shaft 33 is journaled for rotation in and projects through the casing 21 and a pinion 34 is 20 fixed to the forwardly projecting end portion thereof and is in mesh with and adapted to be driven by the pinion 31. The rearwardly projecting end portion of the shaft 33 is suitably secured to and adapted to operate 25 the valve 20 of the pressure pipe 18. The countershaft 31^a is also formed with a crank arm 35 on its forwardly projecting end portion, beyond the pinion 31.

Bearings 36, 37 are fixed to the front wall 30 or plate of the furnace 10 and a shaft 38 is mounted for rotation or rotary oscillation therein, in upright position. The upright shaft 38 is formed with a crank arm 39, projecting rearwardly, on its upper end portion, to which is pivotally connected one end portion of a pitman or connecting rod 40 extending transversely across the front of the furnace toward the casing 21. The pitman 40 is removably connected, as by an up- 35 standing hooked arm 41, to the crank arm 35 of the countershaft 31^a, and said hooked arm 41 preferably is adjustably secured to said pitman 40. In this instance I have shown the hooked arm 41 as being ap- 40 tured to fit loosely the pitman 40, which is threaded and has nuts 42, 43 screwed thereon on opposite sides of said arm. The pindle rods 44, 45 of the draft doors 13, 14 are secured to said doors by hinge members 46 45 and are mounted loosely in hinge members 47 carried by the furnace plate. The pindle rods 44, 45 are formed with rearwardly projecting cranks 48, 49 on their upper ends. Oppositely extending arms 50, 51 are fixed 50 to the lower end portion of the upright shaft 38 and are formed with upstanding studs 52, 53 on their ends, to which are pivotally connected the inner end portions of connecting rods 54, 55 respectively. The 55 connecting arms 54, 55 extend in opposite directions transversely of the furnace and are pivotally connected at their outer ends to the cranks 48, 49 respectively. Thus the draft doors 13, 14, which are hinged at their outer margins, are connected to the counter-

shaft 33 and are adapted to be swung to open position by unwinding of the spring 23.

In practical operation, when it is desired to supply fresh fuel through the doors 11, 12, the draft doors 13, 14 are first moved to 70 closed or nearly closed position. The handle 32 is moved to upright position, which results in winding the spring 23 and raising the piston 26 in the cylinder 25. This action also results in opening the valve 20 and 75 admitting steam to the pipe 18 and jets 19, whence it issues through the nipples 16, to the end of setting up a forced draft of air through the pipe 15 and said nipples. This forced draft supplies an abnormal quantity 80 of oxygen to the young fire to the end of consuming the smoke and gases released from the fresh fuel when first heated, and also forcibly breaks up such smoke and gases and mingles oxygen therewith, and the location 85 of the nipples 16 immediately beneath the boiler of the furnace results in placing this combustion where it will be most effective. As soon as the handle 32 is released manually the spring 23 begins to unwind, causing a clockwise rotation of the crank shaft 22 and a similar rotation, through the gears 30, 31 and 34, of the shaft 33, and an opposite rotation of the countershaft 31^a. This movement of the parts is retarded, steadied 90 and governed by the resistance of the fluid 27 in the cylinder 25 to the descent of the piston 26. As the crank 35 moves in the opposite direction to the handle 32, the first result of such movement is a movement to 100 the left of the pitman 40, and then after said crank has passed the horizontal, a movement to the right. The result of the first part of this movement is a counter clockwise oscillation of the upright shaft 38 and a consequent reciprocatory movement of the connecting rods 54, 55 away from the median line of the device, to the end of closing or holding closed the draft doors 13, 14, so that the young fire will not get too much draft 110 from beneath, which would interfere with the thorough consumption of the gases as above described. After the crank 35 has passed the horizontal position, however, in its downward movement, these movements 115 are reversed, and the draft doors 13, 14 are gradually moved to open position as shown in Figs. 2 and 3. When the throw of the crank shaft 22 has completed a half revolution, approximately, it engages the counter- 120 shaft 31^a and is held, thus furnishing a positive stop for the parts while the spring 23 is still exerting its force, whereupon all movement of the parts ceases.

As the shaft 33 is rotated through the 125 action of the pinions 30, 31 and 34 it causes a gradual closing movement of the valve 20, and as the latter pinion is preferably just half the size of the pinion 30, said shaft completes approximately a whole revolution, 130

and acts to completely close said valve at the time the parts have reached their ultimate positions as above described, whereupon the flow of steam or compressed air is stopped 5 and the forced draft discontinued. Thereafter the fire receives the desired draft from below, and the draft doors 13, 14 may be left in open position or regulated as desired manually. The hooked arm 41 may be disconnected from the crank 35 until such time 10 as the controlling mechanism is again desired for use, upon adding fresh fuel to the fire.

This mechanism controls the drafts, both 15 the lower draft and the forced draft, and the furnace requires no attention from the fireman after the addition of the fuel and setting of the device as above described.

It is obvious that the device may be adapted 20 for use on either side of the furnace, and that various modifications of the various cranks, arms and connecting members may be employed without departing from the spirit of my invention.

25 I claim as my invention—

1. In a furnace having hinged bottom draft devices and valve-controlled forced draft devices, a motor, a countershaft mounted for rotation, driving connections between 30 said motor and countershaft, connections between said countershaft and the valve of said forced draft devices, an upright shaft mounted for rotary oscillation, said upright shaft and countershaft being formed with 35 cranks on their adjacent ends, a pitman pivotally connecting said cranks, said upright shaft also being formed with oppositely extending arms, connecting rods pivotally connected at one end to said oppositely extending arms, and connections between said connecting rods and said bottom draft devices.

2. In a furnace having hinged bottom draft devices and valve-controlled forced draft devices, a motor, a countershaft mounted 45 for rotation, driving connections between said motor and countershaft, connections between said countershaft and the valve of said forced draft devices, an upright shaft mounted for rotary oscillation, said upright shaft and countershaft being formed with 50 cranks on their adjacent portions, a pitman pivotally connected at one end to the crank of said upright shaft, an arm adjustably secured to the opposite end portion of said 55 pitman and removably connected to the crank of said countershaft, and connections

between said upright shaft and the bottom draft devices.

3. In a furnace having hinged bottom draft devices and valve-controlled forced 60 draft devices, a motor, a countershaft mounted for rotation, driving connections between said motor and countershaft, connections between said countershaft and the valve of said forced draft devices, an upright shaft 65 mounted for rotary oscillation, connections between said countershaft and upright shaft, crank arms fixed to and projecting from said bottom draft devices, oppositely extending arms on said upright shaft, and 70 pivotal connections between said oppositely extending arms and the crank arms of said bottom draft devices.

4. In a furnace having bottom draft devices and valve-controlled forced draft devices, a motor having a crank shaft, a countershaft mounted for rotation, intermeshing pinions on said countershaft and crank shaft, a third shaft mounted for rotation, 75 a pinion fixed to the latter shaft and engaging the pinion of the countershaft, the pinion on the said third shaft being of materially less diameter than the pinion of the crank shaft, connections between the third shaft and the valve of the forced draft devices, connections between the countershaft and the bottom draft devices, and means for 80 positively stopping said crank shaft.

5. In a furnace having bottom draft devices and valve-controlled forced draft devices, a casing, a crank shaft journaled therein, a spring fixed to said casing and crank shaft and adapted to be wound on the latter, a cylinder in said casing provided with an inlet valve and an outlet valve, a 90 piston mounted for reciprocation in said cylinder and connected to said crank shaft, a liquid in said casing and adapted to be forced in and out of said cylinder by the action of said piston, a countershaft journaled in said casing, driving connections between the crank shaft and countershaft, connections between said countershaft and the valve of the forced draft devices, and 95 connections between the countershaft and the bottom draft devices.

Signed by me at Des Moines, Iowa, this 9th day of November, 1914.

ELI R. GREENE.
